US0D1071857S

(12) **United States Design Patent** (10) **Patent No.:** **US D1,071,857 S**
(45) **Date of Patent:** ** Apr. 22, 2025

(54) **PORTABLE POWER SUPPLY**

(71) Applicant: **Shenzhen Jiahongjing Technology Co., Ltd.**, Shenzhen (CN)

(72) Inventor: **Zhongci Yin**, Shenzhen (CN)

(73) Assignee: **Shenzhen Jiahongjing Technology Co., Ltd.**, Shenzhen (CN)

(**) Term: **15 Years**

(21) Appl. No.: **29/849,425**

(22) Filed: **Aug. 11, 2022**

(51) LOC (15) Cl. 13-02

(52) U.S. Cl.

USPC **D13/108**

(57) **CLAIM**

The ornamental design for a portable power supply, as shown and described.

DESCRIPTION

FIG. 1 is a first perspective view of a first embodiment of a portable power supply showing my new design;

FIG. 2 is a second perspective view of the first embodiment thereof;

FIG. 3 is a front view of the first embodiment thereof;

FIG. 4 is a back view of the first embodiment thereof;

FIG. 5 is a left side view of the first embodiment thereof;

FIG. 6 is a right side view of the first embodiment thereof;

FIG. 7 is a top view of the first embodiment thereof;

FIG. 8 is a bottom view of the first embodiment thereof;

FIG. 9 is a first perspective view of a second embodiment of a portable power supply showing my new design;

FIG. 10 is a second perspective view of the second embodiment thereof;

FIG. 11 is a front view of the second embodiment thereof;

FIG. 12 is a back view of the second embodiment thereof;

FIG. 13 is a left side view of the second embodiment thereof;

FIG. 14 is a right side view of the second embodiment thereof;

FIG. 15 is a top view of the second embodiment thereof;

FIG. 16 is a bottom view of the second embodiment thereof;

FIG. 17 is a first perspective view of a third embodiment of a portable power supply showing my new design;

FIG. 18 is a second perspective view of the third embodiment thereof;

FIG. 19 is a front view of the third embodiment thereof;

FIG. 20 is a back view of the third embodiment thereof;

FIG. 21 is a left side view of the third embodiment thereof;

FIG. 22 is a right side view of the third embodiment thereof;

FIG. 23 is a top view of the third embodiment thereof; and,

FIG. 24 is a bottom view of the third embodiment thereof.
